UNITED STATES PATENT OFFICE.

JOHN H. STONE, OF BUFFALO, NEW YORK.

ROLLER AWNING.

Application filed February 18, 1922. Serial No. 537,598.

To all whom it may concern:

Be it known that I, JOHN H. STONE, a citizen of the United States, residing at Buffalo, in the county of Erie and State of New York, have invented certain new and useful Improvements in Roller Awnings, of which the following is a specification.

This invention relates to an improvement in roller awnings and more particularly to means for regulating the operation thereof.

Certain of the objects of this invention are to provide means which will prevent the lowering and raising of such an awning by a continued rotation of the awning roller in the same direction by positively stopping such rotation when the foot rod has reached a position already predetermined; which will consequently insure uniformity in appearance and regulate the tension on the awning fabric; which will prevent any undue strain upon the side wings; and which can be quickly and securely adjusted.

Other objects will appear from an examination of the following description taken in connection with the accompanying drawings which form a part thereof and in which

Fig. 1 is a front elevation of a roller awning provided with one embodiment of this invention;

Fig. 2 is an enlarged plan view of the embodiment of this invention taken along the line 2—2 of Fig. 1;

Fig. 3 is a rear elevation of such embodiment;

Fig. 4 is a transverse longitudinal section taken along the line 4—4 of Fig. 2;

Fig. 5 is another longitudinal section taken along the line 5—5 of Fig. 2; and

Fig. 6 is an enlarged cross section of the awning roller and intermediate support taken along the line 6—6 of Fig. 1.

Referring to the drawings Fig. 1 shows somewhat diagrammatically a roller awning installation of the usual type with which is assembled a regulating device designated by the numeral 10 which embodies one form of this invention.

This awning installation comprises the roller 11 to which one end of the awning fabric 12 is secured. A foot rod 13 hinged by any suitable means to the building on which the awning is installed is secured to the fabric near the bottom. The roller 11 is operated by a vertical shaft 14 having at its upper end a gear 15 in mesh with a

gear 16 on the roller. A gear box 17 actuated by a handle 18 is suitably joined to the lower end of the shaft 14. The roller 11 is supported at each end by straps or sockets 19 and intermediate its ends by a bracket 20 which almost completely encompasses the roller and the fabric around it.

Side wings 12^A separate from the main fabric 12 are fastened at their upper ends to the building and at their lower ends to the foot rod 13. Thus when an awning having these side wings is lowered the descent of the foot rod will be stopped when the side wings are taut. In order to relieve these wings from undue strain and to insure that the foot rod will always stop at the same point whether or not the awning includes side wings the regulating device forming the subject of this invention is used.

This regulating device 10 comprises a threaded rod 21 pinned at its lower end to a socketed connector 22 which turns with a squared bar not shown projecting from the box 17. At the upper end of the shaft is a cup shaped member 23 through which it is joined to the rod 21. Mounted on the rod 21 is a nut 24 here shown as of rectangular contour.

Surrounding the rod 21 is a casing comprising a back plate 25, and a front plate 28; the former having an upper central forward projection 26 through a hole 27 in which the shaft 14 extends into engagement with the rod 21. The front upper edges of the plate 25 and the front and side edges of the projection 26 have flanges 29 which overlap the upper edges of the front plate 28, thus protecting the interior from rain or snow. The plate 28 is U-shaped and has flanges 30 at each side of the central portion, which flanges are secured to the back plate 25. The side walls 32 of plate 28 provide a pocket 31 for the rod 21 and nut 24 when the casing is assembled. As shown particularly in Fig. 4 the side walls 32 of the pocket are substantially in contact with two opposite flat sides of the nut 24 hence the nut is held from rotation with the rod 21 but must travel axially thereon. For example Figs. 4 and 5 show two of the different positions which will be assumed by the nut.

The bracket 20, see Fig. 6, comprises a plate 33 having upper and lower curved arms 34 and 35 respectively between the outer ends of which is the throat or opening 36. The arms extend above and below

- the roller 11 and carry a plurality of rolls 37 which contact with the awning fabric. The fabric on the roller is led to and from the upper side as shown in Fig. 6 and is guided by the rolls 37 on the upper arm 34. In order to keep the fabric even and smooth it is the practice to provide surplus material which is at all times kept wound up on the roller.
- 10 Before discussing the operation of the regulating device which embodies the subject matter of this invention it will be of advantage to consider the operation of a roller awning installation such as is shown in Fig. 1, not equipped with this device, the gear box 17 being directly connected to the gear 15 by the shaft 14. By turning the handle 18 in the proper direction the roller 11 is rotated to release the fabric 12 which, by the weight of the foot rod 13, is lowered to the position shown in Fig. 1. If, instead of stopping at that point the rotation of the roller 11 is continued the foot rod, if there be no side wings, will 20 drop a trifle lower and then stop because its hinge connections will not permit it to go further. The fabric 12 will, however, continue to unroll until only the inner end which is fastened to the roller remains. 25 If the rotation of the roller is continued the fabric will be wound up again on the roller, this time in the opposite direction so that instead of passing through the throat 36 to the upper side of the roller as in Fig. 35 6 the fabric will pass to the lower side. The end of the lower arm 35 will thus rub against the fabric every time the awning is raised or lowered and after a short time, unless the fabric is rewound so that it feeds 40 to and from the upper side, this friction will wear a hole completely through. If side wings are provided the foot rod will not descend beyond the point at which these wings are taut but the fabric will continue 45 to unroll and will be removed as pointed out above. This is not a mere theoretical supposition but is a condition which arises too often and which is one of the objections eliminated by the use of this invention.
- 50 After the regulating device has been connected to the shaft 14 between the gear box 17 and the gear 15 and the rear plate has been firmly fastened to the building by screws through the holes 38 the outer plate 55 28 is removed. The awning is then lowered to the lowest position desired and when this is reached the nut 24 which is now free to rotate on or with the rod 21 is turned until it bears against the top of the connector 22 with two parallel sides at right angles to the back plate. The front plate is now secured in any suitable way such as by bolts through the holes 39 to the back plate with the nut 24 in the pocket 60 31. As shown in Fig. 4 the nut 24 contacts with the sides of the pocket 31 so that it cannot rotate but will move axially on the rod. Thus to raise the awning the rod as viewed in Fig. 2 must be turned clockwise so that the nut will mount until it occupies a position somewhat as in Fig. 5, while to lower the awning the rod is turned in the opposite direction, the nut being forced by its engagement with the rod to descend until it rests on the connector 22. When this position is reached the nut absolutely prevents any further lowering of the awning and obviously necessitates that any further turning of the handle be in the opposite direction, thus eliminating any possibility of further unrolling the fabric or of winding it up on the roller other than in the way shown in Fig. 6. Moreover this regulating device relieves the gears in the box 17 from strain and in case anything gives way and the awning starts to lower the foot rod will be stopped so that the side wings will not be torn from their fastenings or the awning fabric be torn from the roller.
- While one embodiment only of this invention has been shown and described I am not to be limited thereby since it is obvious that other embodiments can be made without departing from the spirit and scope of the invention as set forth in the following claims.
- Having thus described my invention that which I claim as new and for which I desire the protection of Letters Patent of the United States is the following:
1. In a roller awning installation including a roller, operated by a rotatable shaft, a threaded rod connected to and in line with said shaft, a nut on said rod, a two part casing enclosing said rod and nut, one part when removed permitting rotation of said nut upon or with said rod and when replaced preventing such movement.
2. In a roller awning installation including a roller, operated by a rotatable shaft, a threaded rod connected to and in line with said shaft, a nut on said rod, a two part casing enclosing said rod and nut, one part projecting over said rod and having an opening through which said shaft extends into engagement with said rod, and the other part including a pocket which engages said nut and prevents any movement thereof relative to said rod other than axial, said parts being separable to permit the free rotation of the nut on said rod in order to adjust the length of its axial movement.
- In testimony whereof I affix my signature.

JOHN H. STONE.
